DRAFT STABILIZER

Filed Nov. 23, 1929

UNITED STATES PATENT OFFICE

LYNN C. BEADLE, OF DETROIT, MICHIGAN, ASSIGNOR, BY MESNE ASSIGNMENTS, TO
TIMKEN SILENT AUTOMATIC COMPANY, OF DETROIT, MICHIGAN, A CORPORATION OF
MICHIGAN

DRAFT STABILIZER

Application filed November 23, 1929. Serial No. 409,378.

The present invention relates to draft stabilizers or automatic draft regulating devices for furnaces or other heaters.

As has been set out in the application of 5 Otto Thiel, Serial No. 372,895, filed June 22, 1929, covering a draft stabilizer of which the present invention is a development, the draft through a furnace is caused by the difference in density between gases in the draft conduits, including the furnace, flue and chimney, and that of the surrounding air. It is, 10 of course, a fact that gas when heated occupies more space than when cool and, therefore, its weight per unit volume is less.

15 In furnace installations, therefore, the gas in the chimney and flues being heated tends to rise and the cooler air rushes in through the draft openings in the furnace. When a furnace installation is entirely cool and assuming that the air in the furnace flues and 20 chimney is of the same temperature as that without, there will, of course, be an equilibrium. When, however, a fire is started in the furnace and the gases in the flue and chimney 25 become heated, the draft into the furnace from the outside is automatically produced. The strength or force of said draft will, of course, depend to a great extent upon the difference in temperature of the gases inside 30 the chimney and flue and those outside. Other conditions also influence the force of the draft and among these conditions is the height of chimney and the condition surrounding its upper end.

35 In the ordinary installations of heating systems, therefore, the force of the chimney drafts will vary between rather wide limits and unless the furnaces are given constant attention, the draft will seldom be suited to 40 the greatest efficiency of the installation.

In the economical operation of liquid fuel burning apparatus in furnaces, a constant draft through the furnace is very desirable, but heretofore has been difficult if not impossible of attainment.

45 While the previous device as set forth in the application referred to has been found quite satisfactory in many instances, it has been found also that as the draft increases 50 above the device, the damper member finally

assumes a balanced position, or condition of equilibrium, in which the force of the gases on the underside are balanced by the force of the gases entering the opening so that a further increase in draft above the device is accompanied by a corresponding increase below. 55

Among the objects of the present invention is to move this equilibrium point well outside of the range of draft likely to occur and thereby render the line representing the draft curve as plotted more nearly straight and horizontal under all practical conditions. 60

Other objects will readily occur to those skilled in the art upon reference to the following description and the accompanying drawing in which. 65

Fig. 1 is a view in elevation of the device.

Fig. 2 is a section on line 2—2 of Fig. 1.

Fig. 3 is a section on line 3—3 of Fig. 1. 70

In the drawing, a metal flue pipe is shown at 10 and this may be the pipe leading from the furnace to the chimney. The present device is preferably constructed to include a pipe segment 11 adapted to be set into the 75 pipe 10 and riveted or bolted in place therein.

The pipe segment 11 is provided with a suitable opening 22 and the plate 21 is located within the pipe segment 11, being slightly larger in area than the opening 22 and adapted to completely close the opening when in closed position, forming what in its conventional form is known as a "check" damper or "draft check." 80

The plate 21 is secured to a member 20 85 which is bent upwardly from the plate and then downwardly again to provide means by which the plate may clear the edge of the opening 22 when moving about its hinge. The hinge for the plate is formed by the U- 90 shaped end of an arm 26 to which the member 20 is secured at the base of the U. The side portions of the U are provided with suitable cups for the pointed ends of screws 16 carried in a bracket 15 and fixed in adjusted position 95 by means of the lock nuts 17.

The arm 26 is preferably bent laterally so that it may be substantially parallel with the member 20 and plate 21 but yet clear the bulge of the pipe 10 when the damper is en- 100

tirely closed. The outer end of the arm 26 is provided with a counter weight 27 which is shown as an eccentric member rotatable about the bolt 28 which serves also to fix it in adjusted position.

By rotating the counterweight 27 the initially adjusted position of plate 21 can be accurately made. It is preferred to make the counterweight 27 of a plurality of stampings fixed together in order that different sizes of dampers may be counter-weighted by the use of more or less of the stampings.

In addition to the parts just described, the plate 21 has mounted near its free end a plate 30 having its outer edge curved so that when the damper plate 21 has moved into the flue far enough for the edge 33 of the plate to be near the edge of the opening 22, the curved edge 33 of the plate 30 corresponds quite closely to the adjacent curved edge of the opening. This plate 30 may be secured to plate 21 as by riveting the end 32 to the plate 21 and may be provided with suitable brace members 31 to provide rigidity.

The particular shape of plate 30 depends upon the draft curve desired to be produced and it is not to be understood that a triangular form will necessarily be used. Other shapes than triangular will produce other curves.

The device is intended to be placed preferably in the flue extending from the furnace to the chimney and arranged so that the draft is in the direction indicated in Fig. 2 by the arrow, that is, in the direction adapted to close the opening 22 by the gases acting on the under side of the plate.

The operation of the device is as set out in the prior application, namely as the chimney draft increases and thereby tends to increase the pull on the furnace, the tendency of the outside air to enter the opening 22 forces the plate 21 inwardly and thereby increases the flow through the opening as well as obstructs the flow from the furnace past the opening.

As indicated above, without the plate 30 the plate 21 will assume a balanced position in which the force on the two sides of the plate is substantially equal and any further increase of draft above the plate is accompanied by an increase below.

The plate 30, however, being interposed in the passage through which the outside air enters the pipes tends to cause the entering air to thrust the plate 21 further into the pipe, and as more and more of the plate 30 enters the opening 22, its influence on the plate 21 will be changed because of its changing area. By suitably proportioning the plate 30 and plotting the draft curve, the latter can be made substantially a straight and horizontal line over the entire range of draft likely to occur in the flue.

It will be noted that the plate 30 does not

at any time completely block the draft opening but only offers a resistance to the entering air reaction to which merely serves to force the damper plate 21 further into the stream of flue gases. The latter are at the same time resisting this intrust of plate 21, so that at no time can either the flue or draft opening be completely stopped or the mechanism get into such position as not to be affected by draft variation. The progressive increase in the effective area of plate 30 adds to the force of its intrust as the draft increases in the chimney and therefore more effectively blocks the flue gases under conditions of abnormally increased draft.

It is, of course, to be noted that, if a curve, other than the one mentioned is desired, modification of the contour of plate 30 may be made so as to produce such curve.

In general terms the regulator is designed for use in any duct carrying gases under variable or constant pressure less than atmospheric where it is desired to obtain a regulation of the pressure in advance of the device. The motivating force of the regulator is the difference between atmospheric pressure and the pressure in the duct beyond the regulator, and the range of possible regulation lies between these two limits.

Now, having described the invention and the preferred form of embodiment thereof, it is to be understood that the said invention is to be limited, not to the specific details herein set forth, but only by the scope of the claims which follow.

I claim:

1. An automatic check draft damper for furnaces or other heaters having a flue for combustion gases which flue is provided with an opening in its wall, a plate pivoted to said wall at that end of said opening nearest the furnace and lying within said flue and adapted to open and close said opening, a second plate mounted in upright position near the free end of said first plate on the outer surface thereof, said second plate increasing in width away from said first plate.

2. In combination with a flue having an opening in its wall, a check damper adapted to cover said opening, said damper being pivotally mounted on said flue wall at that side of the opening toward the flue inlet and adapted to move inwardly of the flue to permit air to enter said opening and a plate mounted on the outer surface of said damper and projecting outwardly therefrom so as to offer resistance to the inflow of air into said opening, whereby reactionary forces tend to thrust said damper further into said flue.

3. In combination with a flue having an opening in its wall, a check damper adapted to cover said opening, said damper being pivotally mounted on said flue wall at that side of the opening toward the flue inlet and

adapted to move inwardly of the flue to permit air to enter said opening and a plate mounted on the outer surface of said damper and projecting outwardly therefrom so as to offer resistance to the inflow of air into said opening, whereby reactionary forces tend to thrust said damper further into said flue, there being counterbalancing means for said damper.

5 4. An automatic draft check damper for a furnace or other heater having a flue for combustion gases which flue is provided with an opening in its wall, a plate pivoted to said wall and within said flue and adapted to open and close said opening and moving in a direction counter to the flow of combustion gases, a second plate near the free end of the said first plate on the outer surface thereof and extending outwardly from said surface in position to oppose entrance of air into the opening when uncovered by said pivoted plate, and thru reactionary forces tend to further increase the opening movements of said pivoted plate.
